UNITED STATES PATENT OFFICE.

FRANK J. TONE, OF NIAGARA FALLS, NEW YORK.

ELECTRICAL FURNACE.

No. 834,948.

Specification of Letters Patent.

Patented Nov. 6, 1906.

Application filed September 14, 1905. Renewed April 6, 1906. Serial No. 310,268.

To all whom it may concern:

Be it known that I, FRANK J. TONE, of Niagara Falls, Niagara county, New York, have invented a new and useful Electrical Furnace, 5 of which the following is a full, clear, and exact description, reference being had to the accompanying drawings, forming part of this specification, in which—

Figure 1 shows in plan view a furnace constructed in accordance with my invention. Fig. 2 is a partial side elevation. Fig. 3 is a cross-section on the line III III of Fig. 1; and Figs. 4 and 5 are views similar to Figs. 2 and 3, respectively, showing a modified construction of the furnace.

The object of my invention is to increase the efficiency of electric furnaces and to obtain greater economy and larger output, especially as to furnaces for smelting materials 20 which remain unfused at the working temperature of the furnace. Furnaces of this class are made with their greater dimensions in the direction of the path of the current, the electrodes being coupled at their outer 25 ends to the metal conductor which supplies the electric current and at their inner ends to the conducting-core or charge through which the current traverses the furnace.

I have discovered that the efficiency of 30 such electric furnaces can be greatly increased by making the furnace-walls of removable and transferable sections and providing means for cooling the base portion of the furnace. At the high temperature to which the 35 furnace is exposed the masonry composing the base of the furnace becomes conductive, and a considerable portion of the current, being diverted through it from the central conducting-core, passes through the masonry 40 and is wasted. By keeping the bottom of the furnace cool this loss is prevented, and the efficiency of the furnace is maintained throughout its operation.

By making the walls in sections having reinforcing bodies or frames of metal in which 45 the walls are assembled and held the walls are rendered permanent in character and at the same time movable and transferable, so that a large wall-section can be removed as a 50 single piece without disturbing the bricks of which it is composed. The reinforcing bodies may be frames, made as shown in the drawings, within which a brick lining is built, or they may be constituted by strong wire 55 fabric or expanded metal embedded in a refractory facing of concrete. The sections at

opposite sides preferably converge at the base, and the intervening body of masonry against which they are set is provided with the cooling devices. 60

The medium which I employ for cooling the furnace-bottom is a current or currents of air or water passing through suitable spaces under the furnace and abstracting the heat thereof by convection, and it is important 65 that the cooling medium be so applied as to prevent the formation of a hot place in the masonry, which would afford a path for the electric current to the ground, as above stated. 70

In Figs. 1-3 of the drawings, which represent an ordinary type of furnace, 22 are permanent end walls which support the electrodes 3 by which the current is conducted to the conducting-core which extends through the furnace charge 4. The sections of the side walls are composed of bricks assembled in iron frames 5 and held therein by retaining-lips 6 at the top and bottom. The frame-sections rest upon the floor, several of them 80 being preferably placed end to end. They are shaped so as to converge downwardly, but their lower ends are separated somewhat by an intervening base 7 of bricks which supports the charge at the bottom. Instead 85 of making this base solid I provide air-spaces 88, which extend through it from side to side and afford passages for the circulation of cooling currents of air. These air-spaces by keeping down the temperature 90 of the brickwork prevent the latter from conducting any substantial amount of electric current and cause the working current to traverse the furnace in the normal path provided by the core. 95

In Figs. 4 and 5 I show a modified construction, in which the furnace-bottom is cooled by pipes 8', which are built in the brickwork and are designed to carry water. 100

Various other arrangements of the cooling-spaces may be made by those skilled in the art without departure from my invention, but the forms which I have illustrated are simple and I consider them to be preferable. 105

By suitable modifications my invention 110 may be applied to electric furnaces of any kind wherein the charge and core remain unfused at the working temperature. In such furnaces the resistance is considerably higher than when the charge becomes fused and conducts as an electrolyte, and owing to such higher resistance a greater proportion

of the current would be diverted through the base.

Cooling means applied to the base as distinguished from the walls of the furnace perform a double function, overcoming not only the loss of current by passage through the base and walls between the terminals, but also the diverting of current from either terminal through the ground. The stationary base may be carried across the furnace and the movable side walls may rest upon this base, and other variations may be made without departing from my invention as defined in the claims.

15 I claim—

1. An electric furnace having a side wall or walls of refractory material held together so as to be movable away from the charge, a refractory base, electrodes and interposed 20 conducting material adapted to remain unfused at the working temperature of the furnace, said base being provided with a space for a cooling medium sufficient to prevent substantial diversion of the current through 25 the base; substantially as described.
2. An electric furnace having side walls formed in laterally-movable sections converging toward the bottom and having a stationary base of refractory material, electrodes and interposed conducting material adapted to remain unfused at the working 30 temperature of the furnace, said base being provided with a space for a cooling medium sufficient to prevent substantial diversion of the current through the base; substantially as described.
3. An electric furnace having side walls formed in laterally-movable sections con- 35

tained in metal frames converging toward the bottom and having a stationary base of 40 refractory material, electrodes and interposed conducting material adapted to remain unfused at the working temperature of the furnace, said base being provided with a space for a cooling medium sufficient to prevent 45 substantial diversion of the current through the base; substantially as described.

4. An electric furnace having side walls formed in laterally-movable sections converging toward the bottom and having an 50 intervening stationary base of refractory material, electrodes and interposed conducting material adapted to remain unfused at the working temperature of the furnace, said base being provided with a space for a cooling 55 medium sufficient to prevent substantial diversion of the current through the base; substantially as described.

5. An electric furnace having side walls formed in laterally-movable sections 60 contained in metal frames converging toward the bottom and having an intervening stationary base of refractory material, electrodes and interposed conducting material adapted to remain unfused at the working 65 temperature of the furnace, said base being provided with a space for a cooling medium sufficient to prevent substantial diversion of the current through the base; substantially as described.

In testimony whereof I have hereunto set my hand.

FRANK J. TONE.
